COLLAPSIBLE TUBE

Sylvester Fiore, Coatesville, Pa.

Application April 20, 1932. Serial No. 606,457

3 Claims. (Cl. 221—60)

This invention relates to containers for viscous substances such as toothpaste, dentifrices, toilet substances, etc., and more particularly to collapsible tubes employed for holding such material.

In accordance with the present invention a collapsible tube having an improved closure for the neck thereof is provided, the invention comprehending the provision of such a closure which may be manually controlled from a point adjacent the bottom or rear end of the tube for opening and closing the outlet neck of the tube.

The invention together with its numerous objects and advantages will be best understood from a study of the following description, taken in connection with the accompanying drawing wherein:

Figure 1 is an elevational view of a collapsible tube having the features of the present invention incorporated therein.

Figure 2 is a longitudinal sectional view through the tube on an enlarged scale.

Figure 3 is a perspective view of the closure element or plunger and the rod connected therewith.

Figure 4 is a perspective view of a guide bar.

Figure 5 is a fragmentary sectional elevational view on an enlarged scale illustrating the manner of sealing the guide openings provided for the plunger rod, the rod being shown at its innermost position.

Referring more in detail to the drawing it will be seen that 5 designates generally a collapsible tube which is substantially of conventional construction. The outlet neck of the tube is designated generally by the reference character 5a while the bottom or rear end of the tube is designated generally by the reference character 5b.

My improved closure for the tube comprises a plunger 6 arranged to reciprocate in the neck 5a and opening inwardly of the tube to permit a discharge of the contents of the tube. The plunger 6 at its inner end is provided with a substantially conical head or shoulder 6a adapted to seat against the inner end of the neck 5a when the plunger 6 is in fully closed position as shown in Figure 2.

A guide bar 7 is provided, the same consisting of a flat metal strip, in the present instance; and the bar 7 is arranged within the tube 5 being anchored at one end at the bottom of the tube as suggested in Figure 2. Adjacent its free end the guide bar 7 is longitudinally twisted and then directed laterally as at 7a. An actuating or control rod 8 is shiftable longitudinally of the tube 5, and one end of the rod is slidable through an opening in the bottom side 5b of the tube and

at its outer end is suitably formed as at 8a to facilitate grasping the outer end of the rod to reciprocate it. At its inner or upper end the rod 8 is slidable through an aperture provided in the laterally extending end 7a of the guide bar, and is also suitably fixed to the inner end of the plunger 6. A spring 9 is disposed about the inner or upper end of the rod 8 and is interposed between the laterally extended end 7a of the guide bar and the inner or headed end of the plunger 6, spring 9 normally urging the plunger 6 outwardly to open position.

When it is desired to expel or discharge some of the contents of the tube 5 the end 8a of the rod 8 is grasped, and pulled outwardly thereby moving the plunger 6 inwardly against the action of spring 9 to open position relative to the neck 5a. With the plunger 6 in its inward open position pressure may be applied to the side walls of the tube 5 for expelling a portion of the contents of the tube in the usual manner. To close the tube, all that is necessary, is to release the end 8a of the rod whereby the latter together with the plunger will move under action of spring 9, the plunger 6 being moved outwardly and axially of the neck 5a until the head 6a engages the inner end of the neck, the plunger 6 being then in fully closed position assuming the position shown in Figure 2.

Adjacent the end 8a the rod 8 is reduced as at 8b for accommodation within the opening in the bottom 5b of the tube, and from a study of Figures 2 and 5 it will be apparent that when the rod 8 is in its innermost position the lower shoulder 10 provided at the lower end of the reduced portion 8b serves to close and seal the opening in the bottom 5b, while when the rod 8 is pulled outwardly against the action of spring 9 the upper shoulder 10b will engage the bottom 5b adjacent the opening therein for sealing said opening and thus preventing the material being forced through said opening when pressure is applied to the tube for discharging a portion of the contents thereof through the neck 5a.

Even though I have herein shown and described the preferred embodiment of my invention, it is to be understood that the same is susceptible to changes fully comprehended by the spirit of the invention and the scope of the appended claims.

Having thus described my invention, what I claim as new is:

1. In combination, a tube having an outlet neck, an inwardly opening closure element for said neck, a fixed guide bar in the tube extending

longitudinally thereof and having an apertured lateral end alined with and adjacent said neck, a rod slideable through said lateral end and secured at one end to said closure element, said rod 5 having its opposite end portion extended thru the bottom of the tube and exteriorly of the tube to provide a manipulating part thru which said closure element may be manually moved inwardly and away from said neck and a spring disposed 10 about said rod between said lateral end and said closure element for normally urging the latter outwardly to a closed position.

2. A closure for a collapsible tube comprising a guide bar within the tube anchored at one end 15 to the bottom of the tube, and at a relatively opposite end provided with a laterally extended portion having an aperture concentric to the outlet neck of the tube, a rod having an end portion slideable through an opening in the bottom 20 of the tube and projecting exteriorly of the tube, and a relatively opposite end slideable through the laterally extended end of the guide bar, an inwardly opening closure plunger on the last named end of the rod freely movable within the outlet 25

neck and having an enlarged head at its inner end seating on the inner end of said outlet neck, and resilient means disposed between said laterally extended end of said bar and said plunger for normally urging the latter outwardly to closed 80 position.

3. In combination, a tube having an outlet neck, and also having a bottom provided with an aperture, a plunger rod slidably arranged in said tube and having an end portion extended thru and disposed exteriorly of the tube, and being also provided adjacent said end portion with a reduced part slideable through the opening in the bottom of said tube and presenting inner and outer shoulders for sealing said opening when 85 said rod has been moved in either direction relative to said tube, an inwardly opening closure plunger on the inner end of said rod mounted to reciprocate within said neck and having an enlarged head at its inner end resting on the 95 inner end of said outlet neck; and resilient means for normally urging said closure plunger outwardly to closed position.
